Whittier, Calif., assignors to Products Research Com-
pany, Burbank, Calif., a corporation of California

Filed Jan. 13, 1964, Ser. No. 78,165

Term of patent 14 years

(Cl. D17—1)

FIG. 1.

FIG. 2.

FIG. 4.

FIG. 3.

FIG. 5.

FIG. 1 is a front perspective view of a seat belt buckle member, showing our new design;

FIG. 2 is a side elevational view showing the side opposite that shown in FIG. 1;

FIG. 3 is a top plan view;

FIG. 4 is a front elevational view; and

FIG. 5 is a rear elevational view thereof.

The broken line showing of a tongue plate and part of a buckle base is for illustrative purpose only.

A novel feature of the present design resides in the seat belt buckle member completely shrouding or enclosing the other buckle parts, the seat belt buckle member including a crowned top, depending sides and depending front and rear portions partially enclosing the buckle base at its front and rear ends.

We claim:

The ornamental design for a seat belt buckle member, as shown and described.
